UNITED STATES PATENT OFFICE.

JOHN C. SWINDELL, OF RESERVE TOWNSHIP, ALLEGHENY COUNTY, PENNSYLVANIA.

ANNEALING-FURNACE.

No. 908,902.

Specification of Letters Patent.

Patented Jan. 5, 1909.

Application filed July 23, 1908. Serial No. 444,876.

To all whom it may concern:

Be it known that I, JOHN C. SWINDELL, of Reserve township, in the county of Allegheny and State of Pennsylvania, have invented a new and useful Annealing-Furnace, of which the following is a full, clear, and exact description, reference being had to the accompanying drawings, forming part of this specification, in which—

10 Figure 1 is a longitudinal section of one form of furnace embodying my invention, the section being taken on the irregular line I—I of Fig. 2; Fig. 2 is a horizontal section, taken on the irregular line II—II of Fig. 1; Fig. 3 is a section of a modified form of furnace, taken on the line III—III of Fig. 4; Fig. 4 is a horizontal section, taken on the irregular line IV—IV of Fig. 3; Fig. 5 is a section taken on the irregular line V—V of Fig. 4; 20 and Fig. 6 is a section on the line VI—VI of Fig. 5.

My invention has relation to annealing furnaces of the reversing regenerative type. Heretofore, in annealing furnaces of this type, 25 the circulating ports for the air and gas have been provided at the ends of the furnace only, the circulation of the air and gas and of the products of combustion being from one end of the furnace to the other. Inasmuch as these 30 furnaces are usually arranged to receive two or more series of annealing boxes arranged in parallel transverse rows, it has been impossible to provide for such a distribution of the heat as to cause those portions of the furnace 35 intermediate the rows of boxes to be heated to the same extent as the ends and top portion of the furnace; and in consequence, it has been difficult to obtain a uniform annealing in the furnace.

40 My invention is designed to provide a novel arrangement of the gas and air ports, whereby a uniform distribution is obtained throughout the furnace, and a better and more uniform annealing effect produced.

45 Referring to the form of my invention shown in Figs. 1 and 2 of the drawings, the numerals 2 designate the usual air regenerating chambers at the respective ends of the furnace, and 3 are the gas regenerating chambers. The ports 4 and 5 leading to these 50 chambers are controlled by the usual reversing valves 6 and 7. The furnace shown in these figures is provided with three parallel sets of tracks 8 extending transversely of the furnace, and upon which the annealing boxes 9 are placed, the furnace having the usual

doors 10 at one side. Leading upwardly from each of the air regenerating chambers 2 to the adjacent end of the furnace, are a series of air-ports 11; and leading upwardly from each of the gas regenerating chambers 3 to the adjacent end of the furnace, are a series of gas ports 12. These air and gas ports 11 and 12 are in alternate relation, extending across the end of the furnace, as shown in Fig. 2. Some of the air ports 11 are also provided with a branch 13 which extends longitudinally in the bottom wall of the furnace underneath the adjacent tracks 8, and open upwardly into the furnace chamber between the first two adjacent tracks. The gas regenerating chambers 3 are also provided with a second series of ports 14 which lead upwardly and longitudinally of the furnace, and open into the furnace chamber adjacent to the branch air ports 13. In the drawings I have shown two of the air ports 11 at each end of the furnace as provided with branch ports 14, and each of the chambers 3 as having two of the ports 14. I desire to state, however, that 80 any desired number of these ports 13 and 14 may be provided. By reason of these ports, it will be seen that I provide means for obtaining substantially as high a degree of heat at the intermediate portions of the furnace 85 as at the end and upper portions, so that the boxes 9 are subjected to a substantially uniform heating effect on both sides and at the top.

Figs. 3, 4, 5 and 6 illustrate my invention applied to a smaller furnace, having only two tracks 15 for the annealing boxes 9. In this construction the branch air-ports 16, which correspond to the branch ports 13 before described, and the second series of gas 95 ports 17, which correspond to the ports 14 before described, leading from opposite ends of the furnace open upwardly into the central portion of the furnace chamber intermediate of the two tracks 15, and upon opposite 100 sides of an intermediate partition wall 18.

For the purpose of controlling the amount of air and gas which enter through the several ports, any suitable damper or valve arrangement may be provided. I have shown 105 for this purpose bricks or tiles 19 which can be made to open or close any desired area of these ports. By means of these dampers, the amount of air and gas which enters at the several ports can be definitely controlled, thereby regulating the amount of combustion taking place at different portions of the

furnace. This not only provides for obtaining a substantially uniform heat throughout the furnace, but it also provides for obtaining more heat, if desired, at one part of the furnace than at another part. For instance, it is desirable to produce a greater combustion at that end of the furnace where the doors are located, owing to the fact that more or less cold air will pass these doors and a greater combustion should be produced adjacent thereto in order to compensate for the cooling action of this air.

I believe I am the first to provide an annealing furnace of the reversing regenerative type, in which the combustion takes place entirely within the combustion chamber and to distribute the combustion at different portions of such chamber for the purpose described.

It will be understood that my invention is equally applicable to furnaces having more than three tracks, in which case branch air and gas ports will be provided to open upwardly into the furnace chamber intermediate each pair of tracks, so that in all cases a uniform heating effect will be obtained at those portions of the furnaces. It will also be understood that the form and arrangement of the various ports may be changed, and that the invention may be applied to various types of furnace construction, without departing from the spirit and scope of my invention, since

What I claim is:—

1. An annealing furnace of the regenerative reversing type, having a plurality of supports for the articles to be annealed and also having a plurality of gas and air ports opening into each end portion of the furnace chamber, and other gas and air ports opening into the intermediate portions of said chamber between adjacent supports, the entire combustion taking place within said chamber concurrently at the different gas and air ports; substantially as described.

2. An annealing furnace having a plurality of supports for the articles to be annealed, and also having gas and air regenerators at each end portion thereof, ports leading from the regenerators into the end portions of the furnace chamber, and other ports leading from the regenerators into the intermediate portion of the furnace chamber between adjacent supports, the entire combustion taking place within said chamber concurrently at the different gas and air ports; substantially as described.

3. An annealing furnace having air and gas regenerators at each of its ends, and pro-

vided with a plurality of supports for annealing boxes or other objects to be treated, a plurality of ports leading from the regenerators into each end portion of the furnace chamber, and other ports leading from the regenerators into the furnace chamber at points intermediate of the supports for the annealing boxes, the entire combustion taking place within said chamber concurrently at the different gas and air ports; substantially as described.

4. An annealing furnace having gas and air regenerators at each end, and provided with three parallel transversely extending supports for annealing boxes or other objects being treated, air and gas ports leading into the end portions of the furnace chamber from the regenerators at each end, and additional air and gas ports leading from each set of regenerators, one set of such additional ports opening into the furnace chamber between the two nearest supports, and the other set of additional ports opening into the furnace chamber between the two supports nearest that end of the furnace, substantially as described.

5. An annealing furnace of the regenerative reversing type having a plurality of supports for the articles to be annealed, and also having a plurality of gas and air ports opening into each end portion of the furnace chamber, other gas and air ports opening into the intermediate portion of said chamber between adjacent supports, and damper means for regulating the amount of air and gas delivered to the furnace at the different ports; substantially as described.

6. An annealing furnace of the regenerative reversing type having a plurality of supports for the articles to be annealed, and also having a plurality of gas and air ports opening into each end portion of the furnace chamber, and other gas and air ports opening into the intermediate portions of said chamber between adjacent supports, and separate damper means for each individual port, whereby the amount of gas and air delivered by such port may be separately regulated, and the combustion and heating effect within the furnace be made substantially uniform, or non-uniform, at different portions of the furnace, as may be desired; substantially as described.

In testimony whereof, I have hereunto set my hand.

JOHN C. SWINDELL.
